ATTORNEY

UNITED STATES PATENT OFFICE.

HENRY TILDEN, OF MINNEAPOLIS, MINNESOTA.

VENTILATING AND CHANGING THE TEMPERATURE OF BUILDINGS.

SPECIFICATION forming part of Letters Patent No. 375,228, dated December 20, 1887.

Application filed October 11, 1886. Serial No. 215,845. (No model.)

To all whom it may concern:

Be it known that I, HENRY TILDEN, a citizen of the United States, and a resident of Minneapolis, county of Hennepin, State of Minnesota, have invented a certain new and useful Improvement in Ventilating and Changing the Temperature of Buildings, of which the following is a specification.

My invention relates to the ventilation of buildings and to the heating or cooling of the same; and it has for its object to draw out the foul air and supply fresh pure air of any desired temperature, hot or cold, as desired, by means simple, economical, and efficient. It consists of the construction hereinafter described and claimed.

At the bottom of a large central foul-air-outlet conduit, which may be a large chimney extended to the bottom of the cellar, I build a fire-magazine suitable for burning fuel especially adapted to produce a great deal of flame. For this purpose I build a brick fire-pot with a grate and ash-pit with its walls entirely independent of the walls of the chimney, the front wall being provided with suitable openings for the admission of fuel and the removal of ashes. The top of this fire-pot or magazine is preferably concave and converges to a suitable opening, to which I attach a smoke and flame pipe of considerable length, extending upward within the chimney. The top of this smoke and flame pipe is perforated with a large number of small holes.

Entering the chimney at a point above the fire-pot and below the top of the smoke-pipe are a series of foul-air tubes or pipes communicating with the various rooms to be ventilated. In my preferred construction I have a separate independent pipe from every room to the chimney at the point named. Each pipe communicates with its room by registers in the floor, the pipe being laid between the joists of the floor, and may be formed by the space between two joists, the floor, and the ceiling below. As many registers may be used as may be desired. In rooms of ordinary size I place four registers, one at each corner, the two at each side or end communicating with the pipe or tube formed by the joist immediately below. These ducts thus formed by

space between joists in the floor are continued downward, preferably between the vertical studding in the wall or by channels, if of brick, to a pipe or duct communicating with the chimney, as hereinbefore described; or the two may be connected by a cross-pipe at one end of the room and this cross-pipe have a descending branch connecting with the chimney at the point named. All the rooms to be ventilated are connected in this way to the chimney by independent foul-air-outlet ducts. Independent ducts to each room are preferable to a main duct with channels, for the purpose of securing certain and uniform results. Otherwise interference and disturbance may be caused by drafts and changes of the winds. This is the construction for getting the foul air out when combustion is started in the fire-magazine at the bottom of the chimney.

To supply the fresh air to take the place of the foul air removed, and to have this of any desired temperature, hot or cold, I provide a large intake air-duct communicating at one end with the external atmosphere and at the other with a suitable heating or cooling device through which or over which the air is passed and is heated or cooled to the desired temperature. From this heating or cooling device or a chamber directly connected therewith independent air-ducts made by suitable pipes or channels in the walls or in any suitable way extend to each room opening into the same through a register at the top of the room and preferably through the ceiling in the middle of the room. Independent pipes are used for the same reason as in the case of outlet-ducts. The fresh-air heating or cooling device may be located at any suitable convenient point of the building. If for heating, and a furnace be used, it will preferably be in the basement or cellar, and if its smoke-outlet be through the same chimney which is used to exhaust the foul air, as described, it should connect with said chimney through an opening in said smoke and flame pipe near its lower end somewhere below the perforations in the same.

The foregoing is a general description of my entire construction. It is illustrated in the accompanying drawings, in which like letters refer to like parts throughout, and in which—

Figure 1 is a sectional elevation on line $y'y'$ of Fig. 2. Fig. 2 is a plan view on the line xx' of Fig. 1.

H is the large central chimney extending 5 from above the roof to the bottom of the cellar.

A is the fire-magazine provided with grate a and flame and smoke pipe a'.

B C D are the independent foul-air-outlet ducts from the various rooms.

10 C is the outlet for the first or lowest room. Registers c' c' c' c' c' c' in the corners and middle of the room allow the foul air to pass into the space between two joists below and thence to the duct C and through C to the chimney, 15 as shown, above A, but below top of a'.

B b' b'' is a similar duct from the second floor, there being a separate communicating duct, b, as shown, from each set of registers to the large duct or pipe B. D d' d'' is a similar duct 20 with separate channel d to each set of registers in third floor. By similar arrangements outlet-ducts are provided from all the rooms.

In each duct, as shown in B, is an automatic valve, b'' b''', and stop b''', which will permit 25 the air to pass into the chimney, but will not allow any gases to pass into the duct from the chimney. This is simply a balanced metal valve pivoted within the foul-air duct near the point of entrance to the chimney. The stop 30 b''' prevents the valve from opening from the chimney. This is simply a device to insure perfect security against the admission of gases from the chimney in the case of possible accident. There would be very little danger of 35 such a thing even if no such valve be provided. The small arrows in the ducts B and C show the direction of the movement of the foul air.

E F G are the independent fresh-air-inlet ducts from the fresh-air chamber, where it has 40 been properly heated or cooled by furnace or cooler J, to the various rooms. E e, for example, conduct the fresh air to the first or lowest room. F f do the same to the second room; G g, (not shown,) to the third, and so 45 on. The arrows at E F G and at e and f show the directions of movement of this fresh air.

In the drawings six registers are shown in the floor of each room for the escape of the foul air. In ordinary-sized rooms four registers, one at 50 each corner, will be sufficient. The fresh air is brought from the exterior of the building to the furnace or cooler J by a large intake duct. (Not shown.) E F G, &c., may be connected directly to the furnace J, instead of the fresh-air chamber, as shown in the drawings.

The operation is as follows: Combustion having been started in the fire-pot at the bottom of the chimney, using soft wood or other flame-producing fuel, the smoke-pipe will be filled 60 with flame and smoke, and the air and gases above will be heated and will ascend out of the chimney. This will make a partial vacuum or a column of gases of less tension or weight in the chimney than the air in the various rooms. 65 Atmospheric pressure will force the foul air out of the rooms and into the chimney. At this point it will be commingled with the flame

in the smoke and flame pipe through the perforations in the same. The large quantity of oxygen in this stream of foul air will support 70 and intensify the combustion in the smoke-pipe. Every particle of carbon supplied will be united with oxygen, giving off intense heat, and the resulting chemical and physical changes will continuously produce, or have a tendency 75 to produce, a partial vacuum, and the remaining and resultant gases, after the chemical changes caused by combustion, will be in a heated and highly-expanded state, rapidly ascending out of the chimney. The foul air from the various 80 rooms will be continuously forced by atmospheric pressure into the chimney to fill or prevent the vacuum, keeping up the process continuously, while the fresh pure air will be continuously forced in through the intake 85 duct by atmospheric pressure outside the building and will be discharged constantly into the rooms to replace the foul air withdrawn below, and thus maintain the equilibrium. Intermediate its point of entrance 90 from the exterior and its delivery to the rooms the fresh air is brought to the desired temperature by heating or cooling by passing it through or over a suitable heating or cooling device. Thus the process is complete and continuous, and fresh pure air of any desired temperature is constantly supplied to the various parts of the building. This is done, moreover, in such a way as to avoid drafts. The foul air passes out from the bottom of the room 100 and the pure air passes in from a central register in the ceiling, distributing itself about the room by imperceptible currents in a uniform manner. The entire volume of air in any given room is changed every few minutes, and 105 any number of persons may occupy the same—as in schools and public assemblies—without injury to the health.

The chemical and physical changes in the flame and smoke pipe a' and chimney H are 110 as follows: Carbon being supplied from fire-pot A, and when the system is used for heating by the products of imperfect (or incomplete) combustion from furnace J and meeting and being thoroughly commingled with 115 the vast quantities of oxygen from the foul-air tubes, is completely consumed, producing carbonic acid (with perhaps a little carbonic oxide) and water, (in form of steam,) giving off intense heat and leaving the nitrogen in 120 free condition. By the heat produced all these gases and the steam are heated and in a highly-expanded condition, and constitute a column of much less weight than the air outside or in the rooms. They therefore rapidly ascend out 125 of the chimney and foul air from the rooms is forced in to take their place. There is therefore a constant tendency to the production of a vacuum, which would be produced did not the air from rooms enter to prevent it. Moreover, this tendency continues all the way up the chimney, for as the products of combustion move away from flame-pipe a' they will begin to lose heat, the steam—or vapor will

condense, occupying less volume, and a partial vacuum will be formed, or tend to be formed, prevented only by supply of fresh products from below. Thus the strength of 5 the current and rapidity of movement is maintained to the top of the chimney, and a large number of rooms or large space may be emptied of foul air by a comparatively small outlet. Attention should, however, be given to 10 the matter of proportion. The outlet conduit or chimney should be of a capacity properly proportioned to the rooms or space to be emptied of foul air and to the total fresh-air-inlet pipes.

15 The process has been described as equally well adapted for supplying cool or warm air, and such is the fact. Its general use will be of course to supply warm air, and the system will enable the heating of large buildings at 20 greatly-reduced cost, besides the invaluable boon of pure air; but in hot weather it is equally desirable to cool buildings, and this can be done by simply passing the air through a cooling device instead of through a heating 25 device; or it may be sufficient for ordinary requirements simply to take in large quantities of fresh air from the outside and keep up a rapid circulation without passing the air through a cooler. The large quantity and rapid movement would in ordinary cases keep the temperature low enough for comfort.

The process hereinbefore disclosed and the construction for applying the same are both of my invention.

35 What I claim, and desire to secure by Letters Patent of the United States, is as follows:

1. In combination, central chimney, H, fire pot or magazine A, located in the chimney bottom, provided with the smoke and flame 40 pipe a', terminating below the chimney-top, independent foul-air outlets B C D, provided with automatic valves b'' b''' b''', connecting each with its respective room through registers b' c' d' in the floor of the same and with

the chimney H below the top of a' and above 45 the body of A, independent fresh-air-inlet ducts E F G, connecting at one end through the ceiling by registers c f g, each with its respective room, and at the other, directly or indirectly, with the external atmosphere, and a 50 heating or cooling device, J, intermediate the fresh-air intake and the point of discharge into the rooms, all substantially as described, for the purpose set forth.

2. In combination, central chimney, H, fire 55 pot or magazine A, located in the chimney-bottom and provided with the smoke and flame pipe a', terminating below the chimney-top, foul-air-outlet ducts B C D, connecting each with its respective room at one end and 60 with said chimney at the other end below the top of pipe a', fresh-air-inlet ducts E F G, connecting at one end each with its respective room, and connecting at the other end, directly or indirectly, with the external atmosphere, 65 and a heating or cooling device, J, intermediate the fresh-air intake and the point of discharge into the rooms, substantially as and for the purpose set forth.

3. In combination, a central shaft or chimney extending from above the roof to the bottom of the cellar, a foul-air burning and exhaust-producing fire-magazine located within and at the bottom of said chimney and provided with a smoke and flame pipe extending 70 a short distance up said chimney, but terminating below the top of the same, foul-air-outlet ducts from the various rooms connecting with said chimney below the top of said flame and smoke pipe, and suitable fresh-air-inlet 75 ducts from the external atmosphere to the various rooms, substantially as described, whereby complete and continuous ventilation is secured.
